UNITED STATES PATENT OFFICE

CHARLES J. FUNK, OF CHICAGO, ILLINOIS, ASSIGNOR TO SORENG-MANEGOLD COMPANY,
OF CHICAGO, ILLINOIS, A CORPORATION OF ILLINOIS

DESIGN FOR A WATER SOFTENER CASING

Application filed November 11, 1932. Serial No. 45,884. Term of patent 3½ years.

To all whom it may concern:

Be it known that I, CHARLES J. FUNK, a citizen of the United States, residing at Chicago, in the county of Cook and State of Illinois, have invented a new, original, and ornamental Design for a Water Softener Casing, of which the following is a specification, reference being had to the accompanying drawing, forming part thereof.

The single figure is a perspective view of the water softener casing showing my design.

I claim:

The ornamental design for a water softener casing, as shown.

CHARLES J. FUNK.
